SOUND DETECTING SYSTEM

Thomas A. Read, Scarsdale, N. Y., assignor to
Westinghouse Electric Corporation, East Pitts-
burgh, Pa., a corporation of Pennsylvania

Application June 24, 1941, Serial No. 399,565

5 Claims. (CL 177—352)

This invention relates to sound detecting systems and, more particularly, to a system for detecting the presence of aircraft by means of the sound waves produced in flight.

A particular feature of this invention is that the detecting system in accordance therewith is responsive only to the sound vibrations produced by the plane in flight excluding vibrations of other origin from interfering with the operation thereof.

Another feature of this invention is that the selectivity of the system as to a particular sound wave is automatically maintained irrespective of the magnitude of other vibrations which may be present in the vicinity of the detecting apparatus.

A particular advantage of a system of this type is that the sensitivity to minute sound intensities can be made extremely large, limited only by the critical value of amplification obtainable with vacuum tubes and associated components.

The detecting system herein described operates on the heterodyne principle of wave reception and provides two distinct sound responsive elements. The individual response of any of these elements in the amplifier system fed therefrom produces no effect, whereas simultaneous response of the two elements to one source of sound produces proper frequency components by frequency conversion to be amplified and detected.

Other features and advantages will be apparent from the following description of the invention, pointed out in particularity by the appended claims and taken in connection with the accompanying drawing, in which:

Figure 1 is a general block diagram of the detecting system;

Fig. 2 is a schematic circuit of the entire assembly.

The schematic arrangement herein shown is merely for an illustration of the operation of the detecting system and various modifications may be made in a practical setup without departing from the basic concept of operation. As will be seen from the description which follows, the underlying principle of operation is that two separate sound pickup devices, such as microphones, are so positioned that the sound energy to be detected shall excite simultaneously both microphones. This can easily be achieved by suitable positioning and mounting of the microphones, of which several may be connected to form two groups and so directed that one in each group converges with another one at a certain point. In this manner, a large territory may be covered in which a sound source at any time will simultaneously energize one microphone in each group.

The microphones 1 and 2 are so spaced as to be sufficiently far apart so that sound from any source originating in the vicinity of one will not reach the other.

5 Referring to Fig. 1, two electroacoustical devices 1 and 2 are so positioned that their axes converge at a far distance in the sky. These devices are preferably microphones of the type having directional characteristics which is indicated by the parabolic enclosures 3 and 4.

The microphone 1 is shown to be connected to an amplifier which magnifies the sound energy output of the microphone and transmits this to a mixer stage. The other microphone 2 is similarly connected to an amplifier. However, the output thereof is fed to a balanced modulator. A local oscillator is provided which also feeds the balanced modulator. The output of the balanced modulator is applied to the mixer stage and the 10 output of the mixer stage is fed to an intermediate frequency amplifier. The output of the latter is detected, that is rectified and the magnitude of the rectified component indicated by a suitable indicator.

15 25 The operation of the system will be described in more detail after a thorough understanding of the circuit and the elements comprising the block diagram components of the system above mentioned. Reference is to be had to Fig. 2 in which

30 the schematic diagram illustrates the circuit of the detecting system employing vacuum tubes in various functional applications. In order to simplify the illustration and make the operation easier to understand, individual batteries are

35 shown for the power supply of each vacuum tube. It is to be understood, of course, that these batteries may be replaced either by a common source of battery supply or by power supplies operating from alternating or direct current. The filament 40 circuit for heating the cathodes of the tubes has also been omitted for the sake of simplicity in diagrammatic illustration, inasmuch as it is well known in the art that thermionic vacuum tubes require suitable sources of filament current.

45 The microphone 1 is shown here to be of the crystal variety although any other microphone may be used. It is connected between the grid 5 and the cathode 6 of the tube 7. The battery 8 provides the required bias for the grid electrode.

50 The vacuum tube 7 represents one stage of an audio frequency amplifier of the resistance-capacitance coupled type. The anode 9 connects to the load resistor 10 which is in series between the cathode 6, the plate supply source 11 and the filter resistor 12. The junction point of resistors 10 and

12 is bypassed with the condenser 13. The filter resistor 12, in connection with the condenser 13, increases the response of the amplifier in the low frequency range in that the impedance of the condenser 13 increases with the decrease of frequency whereby the effective load resistance for the tube 7 will also be increased. The output of the amplifier is coupled by means of the coupling condenser 14 to the control grid 15 of the mixer tube 16. The input voltage for the grid 15 may be adjusted by means of the resistor of the voltage divider 17, the return terminal of which is connected in series with the grid bias source 18 to the cathode 19 of the tube 16. The output circuit of the mixer tube 16 between its anode 20 and cathode 19 includes the primary winding 21 of the transformer 22 and the anode supply source battery 23. The primary winding 21 is tuned to resonance to a predetermined frequency by means of the condenser 24. The secondary winding 25 of the transformer 22 connects to the input circuit of the tube 26 comprising the grid 27 and cathode 28. The bias source 29 is in series with the secondary winding 25, the latter being also tuned to resonance to the same frequency by means of the condenser 30. The vacuum tube 26 represents the first stage of an intermediate frequency amplifier being tuned to a predetermined fixed frequency. It is followed by another stage similar in electrical details and construction. Consequently, the following stage needs no separate description and similar components thereof are indicated by identical reference characters bearing primary indices. The vacuum tube 26 is of the screen grid type having its screen grid electrode 31 connected to an intermediate point on the power supply represented by the batteries 32 and 33 in series, the latter supplying also anode voltage between cathode 28 and anode 34 in series with the primary winding 35 of the transformer 22. This winding is tuned by the condenser 36.

The output of the last stage of the intermediate frequency amplifier is fed by means of the transformer 37 to a diode rectifier 38. The secondary winding 39 of the transformer 37 is connected to the anode 40 of the diode 38 and returns through the diode load resistor 41 in series with a current indicating instrument 42 to the cathode 43 of the diode 38. The secondary winding 39 is also tuned to resonance by the condenser 44. The intermediate frequency is by-passed by the condenser 45 connected between the junction point of the winding 39 and the resistor 41 and the cathode 43.

The second microphone 2 is placed in the input circuit of another audio frequency amplifier comprising the tube 49 of which the grid 50 connects to the rider 51 of the voltage divider 52 paralleling the terminals of the microphone 2. A bias source for the grid 50 is indicated by the battery 53 the positive terminal of which is connected to the cathode 54 of the tube 49. The output circuit between anode 55 and cathode 54 includes the primary winding 56 of the push-pull input transformer 57 in series with the anode supply battery 66. The secondary winding 58 thereof is center-tapped, the two terminals being connected to the grids 59 and 61 of the tubes 60 and 62, respectively. The battery 63 in series between the interconnected cathodes 64 and 65 and the center tap provides the initial bias source for the grids 59 and 61. It may be mentioned here, although further reference thereof will be had, that the output of the amplifier tube 49 is applied by means of the divided circuit of the secondary

winding 58 of the transformer 57 in opposite phase to the grids 59 and 61. Similarly, a fixed frequency energizing voltage is applied to the screen grids 67 and 68 of the tubes 60 and 62, respectively. This connection of the tubes 60 and 62 is known in the art as a balanced modulator circuit, whereby certain frequencies may be combined in a desired manner and others eliminated. Circuits of this type are described on page 121 of the book entitled "Theory and Applications of Electron Tubes," by H. J. Reich, 1939 edition.

The other energizing voltage for the screen grids 67 and 68 of the vacuum tubes 60 and 62, respectively, is obtained from a local oscillator operating at a definite fixed frequency. The latter is shown as a crystal controlled vacuum tube oscillator comprising the vacuum tube 70, of which the grid 71 is connected to the cathode 72 through a grid resistor 73. A piezo-electric crystal element 74 shunts the grid resistor and acts in connection with the tuned output circuit as the frequency determining element of the oscillator. The oscillator anode 75 is connected to a tank circuit comprising the primary winding 76 of the transformer 77 tuned by the condenser 78, the anode voltage being applied between cathode 72 and anode 75 from the battery 79. The secondary winding 80 of the transformer 77 forms by virtue of a center-tap a push-pull input circuit. The free ends are connected to the screen grids 67 and 68, respectively, and the center-tap to the voltage source represented by the battery 81 terminating at the cathode 64.

In the arrangement herein shown, the mixer tube 16 and the balanced modulator tubes 60 and 62 are shown to be of the screen-grid type in which the screen grid is utilized also as a second control grid. This type of connection is merely for the purpose of simplification. Other types of tubes may equally be used, particularly those which have auxiliary grids for the purpose of injecting secondary control voltages besides the primary control voltage applied to the signal grid. Tubes of this type are known as mixer or converter tubes. The RCA type 6L7 may be mentioned as an example.

The output circuit of the balanced modulator tubes includes the anode 82 of the tube 60 and the load resistor 83, whereas, for the tube 62, the anode 84 and the load resistor 85. The junction point of the resistors 83 and 85 returns to the anode supply source represented by the battery 86 in series with a common load resistor 87. Across the latter the voltage will be proportional to the sum of the plate currents of the modulator tubes. Since the output of the balanced modulator is derived from the common load resistor 87 by capacity coupling, a condenser 88 is connected to the junction point of the resistors aforementioned and to the resistor 89 which functions as the screen grid load resistor of the mixer tube 16. The voltage supply source for the screen grid 90 is obtained from the battery 91. In the screen grid circuit of the tube 16 in series with the resistor 89 is also a filter comprising the self-inductance 92 tuned by the condenser 93.

In describing the operation of the system it is important to note that the frequency of the oscillator 70 is chosen to be higher than the highest audio frequency to be detected, that is, it is a supersonic frequency and may be of any order of magnitude within limits of practical engineering design. It is also to be noted that this frequency will be the intermediate frequency 75 in the system to which the amplifiers 26 and 26

are sharply tuned. Tuned primary and secondary circuits, as shown, will have adequate selectivity to respond only to the intermediate frequency. In certain practical applications, particularly when the oscillator frequency is chosen to be very high in comparison to the highest audio frequency to be received, it may be advantageous to use the crystal-filter type of coupling in the intermediate frequency amplifier whereby extreme selectivity to a single frequency may be obtained.

For the sake of easier understanding, we may give numerical values to the various frequencies under consideration and by way of example, assume that the frequency of the drone of the airplane has predominant components around 500 cycles. It is, of course, immaterial what the predominant audio frequency emitted by the plane may be, since the system will respond to all frequencies within the audio range. The example given here is purely an arbitrary choice in value in order to explain the operation more easily. The 500 cycle note will excite both microphones 1 and 2 simultaneously when the plane is in the receptive range of the microphones, as shown in Fig. 1. The 500 cycle signal voltage derived from the microphone 1 will be amplified by the tube 7 and appears at the input, that is on the grid 15 of the tube 16. The output circuit of this tube, namely, the primary winding 21, is sharply tuned to a much higher frequency outside of the audio frequency range. To continue our numerical example, let us choose 30,000 cycles for the intermediate frequency. Consequently, the output circuit will be of very low impedance, almost a short circuit for 500 cycles and whatever minute energy may be had at that frequency in the output circuit of the tube 16, it will not be amplified further due to the selective response of the intermediate frequency amplifier to only 30,000 cycles. This illustrates also the fact that any other audio frequency signal which may be applied to the microphone 1 due to external noise as long as it does not reach the other microphone will not produce a voltage in the output circuit of the tube 16 since the output circuit and the succeeding amplifiers do not respond to audio frequencies. As stated before, the microphone 2 is also energized by the 500 cycle note from the airplane. Similarly in the output circuit of the amplifier tube 49, an output voltage at 500 cycles will appear and will be transferred to the grids 59 and 61. Simultaneously the oscillator 70 applies voltage to the screen grids 68 and 67 at a frequency of 30,000 cycles since this was chosen as the intermediate frequency. Consequently in the output circuit of the balanced modulator, namely, at the junction point of the resistors 83, 85 and 87, the sum and difference frequencies will appear. These frequencies will be 30,500 cycles and 29,500 cycles. The 30,000 cycle voltage from the oscillator 70 and the 500 cycle signal voltage will cancel out in the output circuit because of push-pull excitation of both sets of control electrodes. This holds true when the two tubes 60 and 62 are matched and the resistors 83 and 85 of equal value. To take care of any slight disbalance whereby a signal at the intermediate frequency may appear across the resistor 87 and also 89, a filter, comprising the inductance 92 and the condenser 93, is provided in series with the screen grid 90 which forms a parallel resonant circuit at the intermediate frequency. Thus the screen grid 90 of the mixer tube will be supplied only

with voltages at the difference frequencies aforementioned.

In the mixer tube, we had on the signal grid 16, the 500 cycle signal whereas on the screen grid 90 we have two signals of frequencies 30,500 and 29,500. Consequently, in the output circuit, there will appear signal voltages of the following frequencies: the additive component of the audio voltage on the grid 15 and the 30,500 cycles resulting in 31,000 cycles, the subtractive component comprising the 500 cycle signal voltage and the 30,500 cycle voltage giving 30,000 cycles. The mixing of the other component, namely, the 29,500 cycles will also result in the additive relation in 30,000 cycles, whereas in the subtractive relation it will be 29,000 cycles. Therefore, we have frequencies of the order of 31,000, 30,000 and 29,000 cycles. Of these, we have selected in our intermediate frequency amplifier the 30,000 component to which the amplifier is sharply responsive and this voltage will be amplified and applied to the diode detector 38 resulting in a unidirectional current flow, the magnitude of which depends upon the magnitude of the signal applied to the system from the two microphones. The microammeter in this circuit, if we desire to indicate the current flow, will serve as the indicator of the presence of the audio frequency vibrations which were simultaneously applied to the two microphones. Of course a voltmeter may also be used to measure the voltage across the load resistor 41 or other similar indicating instruments, which will indicate the presence of the intermediate frequency signal in the output of the amplifier tube 26.

It is again emphasized that the above frequency values are entirely arbitrarily chosen and the same relationship will hold with respect to any audio frequency signal to which the microphones are capable of response. If we indicate the frequency which is simultaneously converted into electrical currents by the microphones as f_1 and the intermediate frequency supplied by the oscillator 70 as f_2 , it will be seen that in the output circuit of the balanced modulator, we will have the frequencies f_1+f_2 and f_1-f_2 . In the mixer tube in order that the system shall be responsive, we must obtain f_2 that is the intermediate frequency. This is effected by beating the audio signal f_1 with the frequency components obtained from the balanced modulator. This results in the following components:

- (a) $f_1+f_1+f_2$
- (b) $f_1-f_1+f_2$
- (c) $f_1+f_2-f_1$
- (d) $f_1-f_2-f_1$

of these (b) and (c) give the intermediate frequency f_2 . It is clearly seen that in accordance with this invention only such source of audio frequency energy will be intercepted which simultaneously energizes two microphones widely spaced. Therefore, irrespective of the high gain which each amplifier following the individual microphone may have, no noise affecting a single microphone will interfere with the intended operation. It is necessary that the audio signal shall energize both microphones in order to give a beat frequency resulting in the intermediate frequency.

70 I claim as my invention:

1. In a system for detecting the presence of aircraft by sound vibrations emanating from the engine or the propeller thereof, sound pickup devices spaced at a substantial distance from each other and operable to translate said sound vibra-

tions into electrical current variations, a dual channel transmission system for said currents, means in one only of said channels for combining said variations with electrical current variations of a predetermined frequency, means for mixing the resulting combined variations with the said variations from said other channel, and means for selectively amplifying the frequency component corresponding to said predetermined frequency.

2. In a system for detecting the presence of aircraft by sound vibrations emanating from the engine or the propeller thereof, sound pickup devices spaced at a substantial distance from each other and operable to translate said sound vibrations into electrical current variations, a dual channel transmission system for said variations, means in one only of said channels for combining said variations with electrical current variations generated in said system and having a predetermined frequency, means for mixing the resulting combined variations with the said variations from said other channel, means for selectively amplifying the frequency component corresponding to said predetermined frequency, and means for indicating the relative magnitude of the amplified component.

3. In a system for detecting the presence of aircraft in flight by sound vibrations emanating from the engine or propeller thereof, a plurality of sound pickup devices of the electrical-acoustic type spaced at a substantial distance from each other and each producing an electrical current corresponding in frequency to said sound vibrations, a dual channel electrical transmission system, each channel being individually energized from one of said devices, means in one only of said channels for combining the output energy thereof with a locally generated oscillation of a fixed frequency, means for transmitting the resultant sum and difference frequencies and cancelling said fixed frequency, means for mixing said last-mentioned frequencies with the output energy having the frequency of said sound vibrations of the other of said channels, thereby obtaining said fixed frequency, and means for selectively amplifying said fixed frequency energy, and means for indicating the amplitude thereof.

4. In a system for detecting aircraft in flight by audio-frequency vibrations emanating therefrom, a plurality of sound pickup devices of the

electrical-acoustic type spaced at such distance that one is not substantially affected by sound energy originated in the locality of the other, said two devices being simultaneously energized by said audio-frequency vibrations, a dual channel transmission system for audio-frequency currents each individually energized by one of said devices, means for generating currents of a fixed supersonic frequency, means for combining the audio-frequency output energy of one only of said channels with said fixed frequency whereby to obtain the sum and difference frequencies between said audio-frequency energy and said fixed supersonic frequency, means for cancelling said fixed frequency and transmitting said combined frequencies, means for mixing said last-mentioned frequencies with the energy output at said audio frequency of said other channel, thereby obtaining currents at said fixed supersonic frequency, means for selectively amplifying said last-mentioned currents comprising a plurality of amplifying stages sharply tuned to said fixed frequency, and means for rectifying the output energy of said amplifier.

5. In a detecting system for airplanes in flight by means of audio frequency vibrations emitted therefrom, a pair of electroacoustic devices spaced at such distance that one is not affected by sound energy originating in the locality of the other, said devices being so positioned as to be simultaneously energized by said audio frequency vibrations, an amplifier connected to the output of each of said devices, a circuit for connecting one of said amplifiers to the input of a mixer amplifier, a circuit for connecting the output of said other amplifier to the input of a balanced modulator, an oscillator producing energy at a fixed supersonic frequency, circuit means for combining said last mentioned energy with the audio frequency energy in said modulator, circuit means for cancelling said fixed frequency energy from the output of said modulator and transmitting the resultant sum and difference frequencies to said mixer amplifier, an output circuit for said mixer amplifier, a plurality of cascaded stages tuned to said supersonic frequency energized therefrom and a detector for indicating the amplitude of the signal currents produced by said amplifier.
